SCOOTER COASTER

Filed April 24, 1931

Inventor:
Erick Silen

by Lester Sargent
Atty.

UNITED STATES PATENT OFFICE

ERICK SILEN, OF STELLA, WASHINGTON

SCOOTER-COASTER

Application filed April 24, 1931. Serial No. 532,618.

The object of my invention is to provide a novel combination scooter and coaster; to provide a device of this character which does not require clamps for fastening it to the foot; to provide novel and convenient means for carrying the scooter when it is not in use; to provide a novel and convenient brake for the scooter to increase its usefulness as a coaster; and to provide a toy of this character that is small and neat and easy and light to handle and which takes up little room; to provide a scooter which can be readily used on either foot.

I attain these and other objects of my invention by the device illustrated in the accompanying drawings, in which—

Figure 1 is a side elevation of my invention;

Fig. 2 is a section on line 2—2 of Fig. 1;

Fig. 3 is a top plan view of the invention, the major portion of the handle rod 1 being broken away; and

Fig. 4 is a detail perspective view of the brake mechanism, a portion of the brake plate and attaching plate being broken away.

Like characters of reference designate like parts in each of the several views.

Referring to the accompanying drawings, I provide suitable foot plates 2 to which the ends of the wire handle rod 1 are attached, this rod having a bent portion 1a at its upper end to function as a handle element. I provide a foot strap 8 attached to or extending under one of the foot plates 2, this foot strap being provided with a suitable buckle 15 for adjusting same. The element 2, however, may be made of one solid plate if desired instead of two plates.

Attached to the bottom foot plate 2, as shown in Figs. 1 and 2, is a metal strip 3a which is secured by bolts 4 to the foot plates 2. Affixed to plate 3a in a suitable manner as by rivets 13, is a spring plate 3. Spring plate 3 has a U-shaped bend 5 and extends over the wheel on the opposite side of the scooter and carries a brake plate 6 affixed to it as by rivets 14. Brake plate 6 is of sufficient length to frictionally engage both of the wheels on that side of the scooter and it is

provided with the down-turned edge portion 7 as shown in Figs. 1 and 2.

Attached to the foot plates 2 are the frames 9 terminating in axle elements 10 on which the wheels 11 are mounted. Wheels 11 preferably may be provided with the rubber tires 12.

The handle rod 1 is for the purpose of steadyng and balancing the rider and also for use in steering and also to facilitate handling the coaster. It is preferably made of twisted wire thereby making it strong and pliable, the curves in the handle portion 1a being provided for children of different sizes whereby to practically increase the life of the coaster.

The novel brake plate 6 and the novel U-shaped attached plate 3 provides a convenient means for applying the brake. One foot of the rider is placed in the strap 8 in the usual manner and when the scooter is used for coasting the other foot may be placed on the plate 6 either lightly or heavily according as it is desired to apply the brake lightly or heavily. The device makes it possible to safely use the scooter as a coaster.

When the rider gets to the foot of a hill he does not have to unscrew the scooter from his foot or keep track of a key, he can just slip his foot out from the strap 8. The construction of the scooter is such that it can be used on either foot. The toy also has a material advantage in that braking is done with a brake plate and not with the sole of the shoe of the free foot as in the case of the usual scooter, thus saving the child from wearing out his shoes as well as making the toy a safer one for him to use in coasting.

What I claim is:—

1. In a scooter-coaster the combination of wheel foot plates, a brake plate, a U-shape resilient plate to one end of which the brake plate is affixed, the other end of said U-shape plate being operatively connected with the foot plates of the scooter.

2. In a scooter-coaster the combination of foot plates, a handle rod, a brake plate, a spring attached to the foot plates and carrying the brake plates, and a strap secured to

the foot plates and adapted to receive one foot of the rider.

3. In a scooter-coaster the combination of foot plates, a handle rod, a brake plate, a spring attached to the foot plates and carrying the brake plates, and a strap secured to the foot plates and adapted to receive one foot of the rider, said strap being positioned midway of the foot plates whereby either end of

10 the device may be used as the front end and either foot inserted in the strap.

4. In a scooter-coaster, the combination of a foot plate, wheel supported frames attached to the foot plate at both ends of same, a brake plate of sufficient length to engage both wheels on one side of the vehicle, a U-shaped plate to which said brake plate is attached, means for attaching said U-shaped plate to the foot plates and a foot strap affixed to the

20 foot plates.

5. In a scooter-coaster, the combination of a foot plate, wheel supported frames attached to the foot plate at both ends of same, a brake plate of sufficient length to engage both

25 wheels on one side of the vehicle, a U-shaped plate to which said brake plate is attached, means for attaching said U-shaped plate to the foot plates, a foot strap affixed to the foot plates, and a wire handle rod affixed to the

30 opposite side of the foot plate from the brake plate, said handle rod having a reversely bent upper end portion adapted for use as a handle.
